(57) **CLAIM**

An ornamental design for a handle for a bucket, as shown and described.

DESCRIPTION

FIG. 1 is a front perspective view showing my new design of a handle for a bucket;

FIG. 2 is a front view thereof;

FIG. 3 is a left side view thereof, the right side being a mirror image thereof;

FIG. 4 is a top view thereof;

FIG. 5 is a bottom view thereof; and,

FIG. 6 is a front perspective view showing my new design of the handle on a bucket.

The broken line showing in FIGS. 1-6 is for illustrative purposes only and forms no part of the claimed design.
